A. N. WARREN

COMB AND BRUSH

Filed April 22, 1922

Fig. 1

Inventor

26 ALICE N. WARREN,

834 Louis H. Schmidt
Attorney

UNITED STATES PATENT OFFICE.

ALICE N. WARREN, OF RENO, NEVADA.

COMB AND BRUSH.

Application filed April 22, 1922. Serial No. 556,125.

To all whom it may concern:

Be it known that I, ALICE N. WARREN, a resident of Reno, in the State of Nevada, a citizen of the United States, have invented certain new and useful Improvements in Combs and Brushes, of which the following is a specification.

My invention relates to combs and brushes in general, and more particularly, combs and brushes that may be attached to the ordinary vacuum cleaner or the like. It is generally known that dandruff is the greatest cause of falling hair and other diseases of the hair, in that it not only attacks the hair at its root, but so closely covers the scalp as to effectively close the pores of the skin, causing constant itching. The usual effort of remedying this common ailment is by means of soaps or other massaging preparations, which have a tendency to take from the hair its natural oil and break up the particles of dandruff or scurf in such a manner as to render their thorough removal from the hair very difficult, especially in the case of a heavy set of hair.

With reference to live stock, a great deal of attention is given to their frequent currying and brushing, as the animals' health is, in great part, due to their being well cleaned; in fact, as much care should be taken of their cleaning as their feeding, to produce the best results. In their present methods of cleaning, the curry combs are beaten or brushed to free them of the particles of foreign matter, which has a tendency to fall or float about, whereupon, it is again deposited on the same or nearby animals.

To eliminate the aforementioned disadvantages in cleaning the scalp of the dandruff or scurf together with the small particles of loose hair or other foreign matter in a sanitary manner, I have provided a comb or brush of the class described of any desirable metal suitable for die casting or rubber or gutta-percha which is provided with a plurality of hollow teeth, so connected with their body portion as to effectively break up the scurf into minute particles, whereupon they are drawn through the various hollow teeth and into the usual vacuum bag or the like. Due to the novel arrangement of the ends of the teeth, it will be readily seen that they will thoroughly cleanse and invigorate the skin and prevent the scurf, loose hairs or other foreign matter

from flying about when combing or brushing.

My invention consists in the construction of a comb or brush defined by or included within the terms or language of the appended claims.

In the drawing—

Figure 1, is a view in perspective of a brush of one embodiment of my invention, as applied to a vacuum cleaner of the usual type,

Figure 2, is an end view, partially in section through the brush,

Figure 3, is a central section through one of the hollow teeth,

Figure 4, is an end view thereof, and

Figure 5, is a fragmentary view of a comb partially in section, showing another embodiment of my invention.

My invention in the form or embodiment shown in the drawing and briefly described in Figures 1 to 4, comprises a body portion 10, which may be formed of sheet metal, such as aluminum or the like, and is provided with a handle 11, and a suitable nipple for securing one end of a flexible tube 12, the opposite end of the tube 12, being suitably fastened to the vacuum cleaner 13, as at 14. The outer edges of the body portion 10 are curved downwardly and inwardly as at 15, forming a substantially semi-circular groove 16.

For resiliently mounting the plurality of teeth so that the scalp will be gently massaged without any undue scraping, I provide a gum or rubber disc 17, which is slightly curved downward and is provided along its periphery with an upwardly extending and continuous bead 18, and is adapted to snugly fit within the groove 16, of the body portion 10, to prevent any leakage of air around this joint. I prefer to make this an air tight joint without the necessity of gluing or cementing, so that the gum or rubber disc 17, may be readily withdrawn and replaced as for cleaning.

The tubular teeth as shown in Figures 3 and 4, may be die-cast, drawn, or made in any other suitable manner, and comprises a substantially tubular portion 19, provided at its upper or flared end 20, with an annular rim 21, for the purpose of being imbedded within and supported by the gum or rubber disc 17, which may be molded around said rim in any desired manner. An additional rim 22, may be provided a sufficient distance

below the rim 21, to more readily steady each tooth against the rubber disc.

To effectually prevent the inlet openings of the teeth 19, from being clogged or obstructed, I provide a pair of oppositely disposed and upwardly extending openings 23, of sufficient distance from the tip or pointed end 24, that will permit the efficient combing and brushing of the hair. I prefer to make 10 the openings 23, tapered, increasing in size as they get further from the point 24, as is clearly shown in Figure 4, so that the larger particles of scurf will be drawn into the tubes 19, as readily as the smaller particles 15 or dust, which will not have so far to travel before they come into direct contact with the vacuum.

In Figure 5, I have shown another embodiment of my invention in the form of a 20 comb which may be molded into a single form of rubber or like composition, or of any other suitable material and comprises a hollowed body portion 25, a handle 26, and a plurality of integrally formed tubular 25 teeth 27, which are provided with inlet openings 28, as has already been described.

From the foregoing description it can be readily seen that a comb or brush may be made into a great number of desired shapes 30 or forms and of various kinds of material, that will render them most efficient and sanitary.

It will be understood that the embodi-

ments of my invention I have shown and described herein is illustrative only and hence 35 it is not to be taken as imposing any limitation or restriction upon the scope of my invention beyond what is required by the proper meaning of the following claims.

I claim—

1. A vacuum brush or the like, comprising a body portion and a plurality of tubular teeth carried by the body portion and communicating therewith, each of the teeth being provided near their outer end with oppositely disposed and upwardly converging openings.

2. A vacuum brush or the like, comprising a body portion and a plurality of tubular teeth carried by the body portion and communicating therewith, each of the teeth being provided near their outer end with elongated openings which increase in area as they extend away from the end.

3. A vacuum brush or the like, comprising a body portion and a plurality of tubular teeth carried by the body portion and communicating therewith, each of the teeth being provided near their outer end with oppositely disposed and upwardly converging and elongated openings which increase in area as they extend away from the end.

In testimony whereof I hereunto affix my signature.

ALICE N. WARREN.
